UNITED STATES PATENT OFFICE.

THERON TEEETER, OF SOUTH LANSING, NEW YORK.

DESIGN FOR A REIN-HOLDER.

SPECIFICATION forming part of Design No. 29,513, dated October 18, 1898.

Application filed September 26, 1898. Serial No. 691,940. Term of patent 3½ years.

To all whom it may concern:

Be it known that I, THERON TEEETER, a citizen of the United States, residing at South Lansing, in the county of Tompkins and State of New York, have invented and produced a new and original Design for a Rein-Holder, of which the following is a specification.

This invention relates to a new and original design for a rein-holder; and it has for its object to provide a design of this character which shall be both useful and ornamental.

The leading feature of the design resides in a straight body-wire provided at each of its opposite ends with a circular guiding loop or ring lying within the plane thereof and at one side centrally between the terminal loops, with an offstanding intermediate circular loop lying in a plane at right angles to the plane of the terminal loops and joined to the body-wire by a twisted neck.

In the accompanying drawings, Figure 1 is a perspective view of a rein-holder embodying the herein-described design. Fig. 2 is a side view thereof. Fig. 3 is an end view of the holder.

Referring to the accompanying drawings,

the numeral 1 designates a straight body-wire which has the terminals thereof bent to form circular guiding loops or rings 2, which lie within the plane of the body-wire.

In addition to the circular terminal guiding loops or rings 2 the straight body-wire 1 is further provided at one side and centrally between the terminal loops with an offstanding intermediate circular loop 3. The intermediate circular loop 3, which is located centrally between the terminal loops 2, is projected laterally from the body-wire and is disposed in a plane at right angles to the plane of said terminal loops 2, said intermediate loop 3 being joined to the body-wire 1 by a twisted portion or neck 4.

What is claimed is—

The design for a rein-holder herein shown and described.

In testimony that I claim the foregoing as my own I have hereto affixed my signature in the presence of two witnesses.

45 THERON TEEETER.
